CLAIM

The ornamental design for a ceiling light, as shown and described.

DESCRIPTION

FIG. 1 is a front perspective view of a ceiling light showing our new design according to a first embodiment;

FIG. 2 is a rear view thereof;

FIG. 3 is a bottom plan view thereof;

FIG. 4 is a front view thereof;

FIG. 5 is a front perspective view of a ceiling light showing our new design according to a second embodiment;

FIG. 6 is a rear view thereof;

FIG. 7 is a bottom plan view thereof; and,

FIG. 8 is a front view thereof.

Views of the article not shown form no part of the claimed design.

The broken lines in the drawings illustrate portions of the ceiling light which form no part of the claimed design.

1 Claim, 8 Drawing Sheets
